(57)

CLAIM

The ornamental design for a laser engraving device as shown and described.

DESCRIPTION

1.1: Perspective

1.2: Perspective

1.3: Front

1.4: Back

1.5: Left

1.6: Right

1.7: Top

1.8: Bottom

The design is a product configured for laser engraving. The broken lines in the drawings depict portions of the laser engraving device that form no part of the claimed design.

1 Claim, 8 Drawing Sheets
